UNITED STATES PATENT OFFICE.

JOSEPH SPENCER, OF CHICAGO, ILLINOIS.

SASH-BALANCE.

SPECIFICATION forming part of Letters Patent No. 399,216, dated March 5, 1889.

Application filed June 27, 1888. Serial No. 278,377. (No model.)

To all whom it may concern:

Be it known that I, JOSEPH SPENCER, a citizen of the United States, residing at Chicago, in the county of Cook and State of Illinois, 5 have invented certain new and useful Improvements in Sash-Balances, of which the following is a specification, to wit:

My invention relates to certain improvements in sash-balances; and it consists in certain peculiarities of the construction and arrangement of the same, as will be more fully set forth and claimed.

In order to enable others skilled in the art to which my invention pertains to make and use 15 the same, I will now proceed to describe it, referring to the accompanying drawings, in which—

Figure 1 is a plan view with my device in place ready for operation. Fig. 2 is a detail 20 view of the cord-holding sleeve and catch, showing the curved shank. Fig. 3 is a sectional side view showing the eye-plate in position on the sash and the recess or depression for the reception of the hook or catch 25 and cord-sleeve. Fig. 4 is a side view showing the device in position to be detached.

a represents the side bar of the sash, having the usual groove, *b*, for the reception of the cord. At a suitable distance from the 30 top of the sash this groove terminates in a recess, *c*, cut or mortised in the side of the sash adjacent to the sash-frame, for the reception and retention of the cord-sleeve, catch, and eye-plate, as will be presently explained.

35 This recess is formed with a depression sufficient to allow the eye-plate and cord-sleeve and catch to fit snugly and to be flush with the outer surface of the sash when the device is locked. The upper portion of the recess is

40 formed tapering, with the smaller portion toward the top of the sash and the lower portion square, or nearly so, as seen in Fig. 1 of the drawings. At the lower portion of the recess I provide a deeper depression with an 45 incline, *d*, as seen in Fig. 3. The object of this incline is to force the tongue of the catch up against the inwardly-projecting portions of the eye-plate, when the catch is inserted in the T-shaped eye.

50 *e* is a bed-plate, having shoulder *f* and T-shaped eye *g*, and is firmly attached to the frame of the sash by means of screws.

h is a cord-holding sleeve, made, prefera-

bly, of a tapering form, with a funnel-shaped hole for the easy passage of the cord through 55 the same, and for holding the core securely when a knot is tied in the lower end. At the lower end of the cord-sleeve, and flush with the top, I provide projections *i*, which rest on the shoulder *f* of the eye-plate. 60

k is a curved shank connecting the projections of the cord-sleeve with the tongue *l*. This shank is curved, as shown, for the purpose of giving a firmer pressure to the tongue against the under side of the eye-plate, acting as a lever on the shoulder *f* of the eye-plate. 65

The operation of my device is very simple and affords an easy method of removing the sashes when it is desired to glaze or cleanse 70 the glass.

To remove the sash it is necessary to detach the beading from the sash-frame and draw the sash inward, or toward the operator. Then by slackening the cord and drawing the 75 cord-sleeve down to a right angle with the frame the catch is readily removed. To fasten or lock the device, the cord-sleeve is held at a right angle with the sash and the tongue is inserted in the eye till it reaches the bottom 80 of the cavity, when the cord-sleeve is pressed upward into the socket for its reception, the cord tightened, and the sash replaced.

Having thus fully described my invention, what I claim as new, and desire to secure by 85 Letters Patent, is—

1. In a sash-balance, the combination of the bed-plate *e* with the sash *a*, and cord-holding sleeve *h*, having a curved shank, *k*, and tongue *l*, engaging with the bed-plate *e*, substantially 90 as shown and described, and for the purpose set forth.

2. In a sash-balance, the combination of the bed-plate *e*, formed with a depressed flange or shoulder, *f*, and having a T-formed eye, *g*, 95 a cord-holding sleeve, *h*, having a curved shank, *k*, and tongue *l*, adapted to engage said eye *g*, and the sash *a*, formed with a depression, *c*, for the reception of the plate and cord-sleeve and tongue, substantially as shown and 100 described, and for the purpose set forth.

JOSEPH SPENCER.
